UNITED STATES PATENT OFFICE

2,612,678

EMBALMER'S TISSUE SEPARATOR

Jenifer W. Renfro, Cincinnati, Ohio

Application February 13, 1950, Serial No. 143,850

3 Claims. (Cl. 27—21)

1

The present invention relates to certain new and useful improvements on instruments which are expressly adapted for use by embalmers and has reference, more particularly, to a structurally novel instrumentality which may be skillfully and expertly used for separating a blood vessel from surrounding fascia so that the vessel, either vein or artery, may be exposed and accessibly held up and away from the fascia while making an incision with a scalpel.

More specifically, the invention has to do with a tissue separator whose construction and features are such that the user may perform the task with requisite skill in order that the chosen blood vessel may be probed loose and raised sufficiently for cleaning and/or incising the vessel after which the instrument is then turned over or inverted to spread the incision so that the customary vein or arterial tube may be inserted into the vessel for drainage requirements.

In reducing to practice a preferred embodiment of the invention, a probing blade some six inches or so in length and less than an inch in width is provided and the same is constructed from metal, bone, hard commercial plastics, hard rubber or any appropriate material which will withstand the cleavage thrust of the scalpel cutting edge. The instrument takes the form of a "blade" which is substantially semi-cylindrical in cross section so as to provide a flat surfaced scalpel accommodating top, and a convex or cambered bottom surface, the incision being made with the vessel in contact with the top and the convex side being used to bow the apertured vessel and to spread the incision or aperture in an obvious manner.

Novelty is also predicated on a blade of the stated construction wherein the insertable end of the convex side is bevelled to provide a penetrating and piloting tip.

Then, too, novelty has to do with an enlarged head on the opposite end of the instrument which assists in handling the instrument and serves to prevent the instrument from accidentally slipping from under the vessel.

What is more, and perhaps the most outstanding achievement, had to do with a hard metal or equivalent blade with or without the stated facilities but having a flat scalpel accommodating surface wherein said surface is provided with especially arranged and coacting grooves to materially assist in the incision of the vessel and to prevent the operator from cutting himself by systematically anchoring and minimizing the possibility that the scalpel will slip off of the bearing surface provided by said instrument.

2

Other objects and advantages will become more readily apparent from the following description and the accompanying illustrative drawings.

In the accompanying drawings, wherein like numerals are employed to designate like parts throughout the views:

Figure 1 is a perspective view of an embalmer's tissue separating and scalpel accommodating instrument constructed in accordance with the principles of the present invention showing a fragmentary portion of a vessel about to be cut with the aid of the V-shaped groove means.

Figure 2 is a perspective view like Figure 1 showing the scalpel in coaction with the straight groove.

Figure 3 is a perspective view showing the manner in which the instrument is turned through 190° to bring the convex bottom upwardly for bowing the vessel and spreading the incision.

Figure 4 is a cross section on the line 4—4 of Figure 1, looking in the direction of the arrows.

Referring now to the drawings by distinguishing reference numerals and accompanying lead lines, the tissue separator, as a structural entity, is denoted by the numeral 6 and as before stated, is a rigid blade of appropriate dimensions. In shape, as shown in Fig. 2, the body portion of the blade is substantially semi-circular in cross section. This construction is adopted in order to provide a flat scalpel base or platen 8. This is referred to as the "top" and is primarily used for holding the vessel up and away from the fascia to facilitate making the incision. The vessel is denoted at 10 and the scalpel at 12, said scalpel having a handle 14 and a cutting blade 16.

The surface or side of the instrument commonly referred to as the underside or "bottom" is convex as denoted at 18. This convexity is used for bowing or cambering the vessel 10 so that the incision 20 will be spread open for insertion of a vein or arterial tube (not shown).

There is a circular head 22 at one end of the instrument having flat and convex surfaces and at the opposite end of the convex side the instrument is camfered or otherwise beveled as at 24 to provide a probing and piloting tip 26.

The features so far described are important but the main new development with which I am essentially concerned is the ways and means on the flat top 8 which assists in performing the cutting operation with the scalpel and at the same time provides an anti-slipping surface for the scalpel blade. Practice has shown that it is desirable that this be accomplished through the provision of simple grooves. There is a linearly straight groove 28 which is especially adapted for

use by some embalmers. In addition, there is a V-shaped groove, that is V-shaped in top plan, whose branches are denoted at 30 and 32. Preferably the adjacent or coacting end of the straight groove merges into and lines up with the crotch in the V. The groove 28 is for making a straight incision. The grooves 30 and 32 are for making a V-shaped incision, which is preferred by some operators. The grooves themselves are preferably V-shaped in cross section and constitute a definite safety factor as they prevent the operator from injuring himself due to the scalpel slipping from the so-called platen 8. The piloting tip means is to facilitate the entrance into the tissue when initially probing and preliminary to separating the blood vessel from the surrounding fascia.

To incise the vessel the separator is slipped under the vessel with the grooved or flat side up and the scalpel is pressed upon the vessel over the groove, making it unnecessary to use a slicing motion but merely to press the scalpel into the groove, thus quickly and safely cutting the vessel.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. A tissue separating instrument of the class shown and described comprising an elongated probing blade adapted to separate a vein or artery from the surrounding fascia and to expose and accessibly hold the same up and away from the fascia while making an incision with a scalpel, said blade having a relatively large disk-like head at one end, being substantially semi-cylindrical in cross section and providing a flat surface on one side and a convex surface on the other side, being beveled at the opposite end to provide a

piloting tip, a groove of V-shaped form provided in the flat side adjacent the head, and a second straight groove having one end merging into the crotch portion of the V-shaped groove.

5 2. A tissue separating instrument of the class shown and described comprising an elongated probing blade adapted to separate a vein or artery from the surrounding fascia and to expose and accessibly hold same up and away from said fascia while making an incision with a scalpel, one surface of said blade being flat and constituting an incising platen for the scalpel, said surface having scalpel receiving guiding and anti-slipping means to safeguard the operator and said means embodying a long linearly straight groove and a companion V-shaped groove at one end of the straight groove.

10 3. A tissue separating instrument of the class described comprising a readily insertable and removable elongated probing blade adapted to separate a vein or artery from the surrounding fascia and to expose and accessibly hold same up and away from said fascia while making an incision in said vein with a scalpel, one surface of said blade being flat and constituting an incising platen for the scalpel, the remaining surface, opposed to said platen, being convex and constituting a vein bowing, stretching and incision spreading surface, said flat surface being provided at one end with a groove which is V-shaped in top plan and V-shaped in cross-section, and being further provided with a second groove which is straight from end to end with one end merging into the crotch portion of said V-shaped

15 groove.
